CLAIM

The ornamental design for a sanitary napkin, as shown and described.

DESCRIPTION

FIG. 1 is a perspective view of a sanitary napkin, showing our new design;

FIG. 2 is a top plan view thereof;

FIG. 3 is a bottom plan view thereof;

FIG. 4 is a front view thereof;

FIG. 5 is a right-side view thereof;

FIG. 6 is an enlarged cross-sectional view taken along line 6-6 of FIG. 8;

FIG. 7 is an enlarged cross-sectional view taken along line 7-7 of FIG. 8; and,

FIG. 8 is an enlarged portion view thereof, illustrating the region indicated by 8 in FIG. 2.

The broken lines in the drawings illustrate portions of the sanitary napkin that form no part of the claimed design. The rear view is omitted because it is the same image as the front view. The left-side view is omitted because it is the same image as the right-side view.
